UNITED STATES PATENT OFFICE.

JOHN EMIL JOHNSON, OF BRAINERD, MINNESOTA.

SCREEN-DOOR ATTACHMENT.

1,025,746.

Specification of Letters Patent.

Patented May 7, 1912.

Application filed August 8, 1911. Serial No. 643,028.

To all whom it may concern:

Be it known that I, JOHN EMIL JOHNSON, a citizen of the United States, and a resident of Brainerd, in the county of Crow Wing and State of Minnesota, have invented 5 a new and Improved Screen-Door Attachment, of which the following is a full, clear, and exact description.

My invention relates to an attachment for 10 screen doors, and is especially adapted to be connected to the top of the door and to the top of the door casing, whereby when the door is opened, the entrance of flies into a room may be prevented.

15 An object of my invention is to provide a new and useful attachment for screen doors, which attachment is made up of a number of supporting rods of similar construction together with a suitable flexible material 20 carried by the rods, said attachment being engaged by the screen door and the door casing, so that when the door is opened the attachment will be expanded, coming back into folded position when the door is closed.

25 A further object of my invention is to provide an attachment of the class described, which will consist of few parts, which may be produced at low cost, and which will be efficient in its operation.

30 Reference is to be had to the accompanying drawings, forming a part of this specification, in which similar characters of reference indicate corresponding parts in all the figures, and in which—

35 Figure 1 is a perspective view showing my attachment in position; Fig. 2 is a similar view showing the position of the supporting rods when the door is open; Fig. 3 is a perspective view of the bearing member; Fig. 4 is a partial sectional view 40 through the casing and door, showing the attachment in folded position; Fig. 5 is a perspective view of the attachment removed from the door; Fig. 6 is a sectional view on the line 6—6 of Fig. 5, showing the method 45 of securing the rods to the flexible material; and Fig. 7 is a perspective view of the rod carried by the casing.

50 My device is adapted to be positioned adjacent the top of any suitable screen door 1 and casing 2, the device being made up of a plurality of similar rods 3 together with a piece of suitable material 4 secured to the rods.

55 A suitable bearing member 5 secured to one side of the screen door in any suitable

manner, is provided with a number of alined openings 6 in the upper and lower portions 7 and 8 thereof, the supporting rods 3 being designed to be rotatably supported in these openings. A suitable rod 9 is secured at its ends to the inside of the door 1, and another rod 10, preferably of the shape shown in Fig. 7, is secured to the top of the casing 2, so that when the door is closed, 60 this rod 10 will be adjacent the rod 9, a rod 11 similar to the rod 9 being secured to the top of the casing 2 and closely adjacent the rod 10. 65

The upper part of my attachment is composed of any suitable flexible material 12, such as cloth, netting or the like, and is preferably of rectangular shape and provided with a plurality of folds 13, within which the rods 3, 9 and 11 are adapted to 70 be engaged, each of these folds being preferably formed by stitching the material as particularly shown in Fig. 6. If so desired, the edges of the material may be hemmed in order to present a pleasing appearance, but 75 such is not essential.

Referring particularly to Fig. 2, it will be noted that each of the rods 3 is provided with an offset end 14, which ends are adapted to engage in the bearing 5, the other ends 85 of these rods lying preferably in the same plane as the fixed rods 9 and 11, the material 12 being secured to the rods as shown in Fig. 1, so that when the door is opened, the device presents a fan-like appearance. 90

In opening the door 1, the flies which are outside of the room seldom enter through the bottom or side portions of the door opening because of the person passing through. The top of the door opening, however, provides an unobstructed entrance. With my device, when the door is opened, the flies which generally congregate around the top of the door because of the warmer and stiller air, will be prevented from entering the room because of my attachment. The device is adapted to fold up closely and neatly when the door is closed, as shown particularly in Fig. 4, the rod 10 carried by the top of the door casing affording a convenient stop against which the plaits or folds of the material 12 will abut in order to hold them closely and regularly together within the casing. 100

The device is adapted for attachment to 110 doors which open from either side, and may be attached to any swinging door of any

size, and the materials of which the various parts of the attachment may be varied at will and in order to suit individual taste without departing from the spirit and scope 5 of the invention as defined in the following claim.

Having thus described my invention, I claim as new and desire to secure by Letters Patent:

- 10 An attachment of the class described comprising a plurality of rods of similar construction and each provided with an offset end, a bearing having opposite end portions provided with a number of openings in
- 15 which the said offset ends of the rods engage, the bearing being adapted to be secured to a door casing adjacent the top thereof, a quantity of suitable flexible material engaging each of the said rods, a rod

adapted to be secured to the door adjacent 20 the top of the casing, one end of the said material being secured to the rod, another rod adapted to be secured to the top of the casing adjacent the said bearing, the other end of the said flexible material being secured 25 to the said rod, the top of the casing being also provided with a rod extending downwardly therefrom against which the folds of the said material are adapted to engage when the door is closed.

In testimony whereof I have signed my name to this specification in the presence of two subscribing witnesses.

JOHN EMIL JOHNSON.
